[57] **ABSTRACT**

A system for automatically searching out a desired frame from a microfilm travelling along a guide path by counting the number of detected pulses generated in response to optical detection of each blip printed on the corresponding blank space of each frame of the microfilm is known. In accordance with a feature of this invention, detected pulses are generated from a group of photosensitive means so as to have directional information and sequential information. Moreover, additive counting-pulses and subtractive counting-pulses are generated in response to only the travelling direction of the microfilm.

SYSTEM FOR AUTOMATICALLY SEARCHING OUT A DESIRED FRAME FROM A MICROFILM TRAVELLING ALONG A GUIDE PATH

This invention relates to systems for automatically searching out a desired frame from a microfilm travelling along a guide path.

In these systems, "blip" printed on the blank space of each frame of the travelling microfilm are usually detected by the use of photosensitive means, such as a phototransistor, and detected pulses are applied to a control device to count the number of the detected pulses so as to perform necessary control. In detecting respective blips, photosensitive means are arranged on a projected screen so as to recognize the magnitude of each blip at the projected screen. Moreover, one of four sides of each rectangular blip is determined as a reference side, and passing of this reference side is detected by the photosensitive means at the projected screen as input signals of a counter performing addition operation or subtraction operation in counting the number of the detected pulses. Accordingly, the system is designed so that the stop position of the travelling microfilm can be correctly controlled for both the normal travelling direction and the reverse travelling direction without mis-counting caused by spots, blots and dusts etc. on the microfilm.

In a system proposed by the inventor in the Japanese Patent application No. 1706/1968, two groups of photosensitive means are provided so that an additive counting-signal combined with an additive instruction-signal is generated when one of the two groups of the photosensitive means is just covered by the blip shifted on the screen, and so that a subtractive counting-signal combined with a subtractive instruction-signal is generated when the other of the two groups of the photosensitive means are just uncovered after complete covering by the shifted blip. In other words, the two groups of the photosensitive means generate respectively detected pulses in response to every time at which the one group of the photosensitive means are just covered by the shifted blip and in response to every time at which the other group of the photosensitive means are just uncovered as mentioned above irrespective of the travelling directions of the microfilm. However, the additive instruction-signal and the subtractive instruction-signal are related to the normal and reverse travelling directions of the microfilm. In this system, if the two end parts of the travelling microfilm are respectively wound on reels so as to have different hardness of roll of the microfilm, this microfilm is often shifted at the initial time of driving in an incorrect direction where the microfilm is shifted in the subtract direction even if this microfilm is driven by a driving mechanism in the additive direction by way of example. Moreover, forward and reverse fluctuations of the travelling microfilm along the travelling direction are often caused when the brake is applied to the driving mechanism at the switching of the driving speed. In this case, errors are caused such that a single blip is repeatedly counted, and such that the number of two frames shifted in the reverse direction is additively counted by way of example.

An object of this invention is to provide a system for automatically searching out a desired frame from a microfilm travelling along a guide path without error even if the microfilm is irregularly driven along the guide path.

In accordance with a feature of this invention, the detected pulses are generated from a group of photosensitive means so as to have directional information and sequential information. Moreover, additive counting-pulses and subtractive counting-pulses are generated in response to only the travelling direction of the microfilm irrespective of the driving direction of the microfilm.

In a summary, a system of this invention is proposed to automatically searching out a desired frame from a microfilm travelling along a guide path by counting the number of detected pulses generated in response to optical detection of each rectangular blip printed on the corresponding blank space of each frame of the microfilm. The system of this in-

vention is provided with two groups of photosensitive means, conformation means, memory means and output means. Each group of the photosensitive means are arranged on the screen of the microfilm so as to detect the length of the rectangular blip on the screen. The confirmation means confirms the length of the blip in response to ON-states of all the photosensitive means in view of directional information. This directional information is determined in the order of switching into the ON-states of respective photosensitive means included in predetermined one of the two groups of the photosensitive means selected in accordance with the travelling direction of the microfilm. The confirmation means generates a confirmation signal when all the photosensitive means included in the other of the two groups become ON-states in accordance with a direction defined by the directional information. The memory means stores the directional information during a time between adjacent two of the confirmation signal. The output means sends out the confirmation signal as the detected pulse only when the directional information corresponds to the predetermined travelling direction of the microfilm.

The principle, construction and merits of the system of this invention will be better understood from the following more detailed discussion taken in conjunction with the accompanying drawings, in which similar parts are designated by the similar reference numerals, characters and symbols, and in which:

FIG. 1 is a fragmentary plan plane view explanatory of a microfilm used in the system of this invention;

FIG. 2 is a constructive diagram explanatory of the optical construction of the system of this invention;

FIG. 3 is a plan view illustrating the relationship between a blip and photosensitive means at the screen of the microfilm;

FIG. 4 is a block diagram illustrating an example of means for detecting a detected signal from the photosensitive means used in the system of this invention;

FIG. 5 is a block diagram illustrating an example of memory means used in the system of this invention;

FIG. 6 is a diagrammatic view of block diagrams explanatory of an example of a circuit for sending out confirmation signals and additive or subtractive counting-pulses used in the system of this invention;

FIG. 7 is a diagrammatic view of diagrams explanatory of relative positions between a shifted blip and a group of photosensitive means in a case of the normal travelling of the microfilm;

FIG. 8 is a diagram of time charts illustrating respective wave forms of the photosensitive means at the relative positions shown in FIG. 7;

FIG. 9 is a diagram explanatory of relative positions between a shift blip and a group of photosensitive means in a case of the reverse travelling of the microfilm; and

FIG. 10 is a diagram of time charts illustrating respective wave forms of the photosensitive means at the relative positions shown in FIG. 9.

With reference to FIGS. 1 to 3, a microfilm used in the system of this invention and the optical construction of the system of this invention will first be described. In FIG. 1, a part of microfilm 1 has a plurality of frames 2 and a plurality of rectangular blips 3 printed on blank spaces so as to correspond to respective frames 2. In each of the frames 2, information patterns (e.g.; characters, drawings, etc.) to be searched out are recorded. In FIG. 2, the system illustrated provided with a light source 4, a condensing lens 5, reels 6 and 6a, a microfilm 7 having the construction shown in FIG. 1 and travelling in the normal direction and the reverse direction between the reels 6 and 6a, a projecting lens 8, a mirror 9, a

screen 10, and photosensitive means 11 (e.g.; phototransistor) whose sensing parts are arranged on the same plane as the screen 10. In accordance with this construction, the contents of each frame 2 and each blip 3 are projected on the screen 10 and shown by a reference 12 and a reference 13 respectively.

The above-mentioned optical system has an optical construc-

tion similar to a conventional enlarger. The light from the light source 4 passes through the condensing lens 5, the microfilm 7 and the projecting lens 8 and is reflected by the mirror 9, so that the images of the information patterns recorded on the microfilm 7 are obtained on the screen 10. A plurality of photosensitive means 11 from two groups (11a, 11b and 11c) and (11d, 11e and 11f) so that each group can confirm the length of the image 13 of the blip 3. In other words, respective distances from the photosensitive means 11a(or 11d) to the photosensitive means 11c(or 11f) are substantially equal to the length of the image 13 of the rectangular blip 3. Moreover, a space between the photosensitive means 11c and 11d is narrower than other spaces.

With reference to FIG. 4, respective outputs of the photosensitive means 11a(A), 11b(B), 11c(C), 11d(D), 11e(E) and 11f(F) are reshaped in reshapers 14a, 14b, 14c, 14d, 14e and 14f respectively and the polarities of respective reshaped outputs are inverted in inverters 15a, 15b, 15c, 15d, 15e and 15f respectively as digital outputs $\bar{A}_1$, $\bar{B}_1$, $\bar{C}_1$, $\bar{D}_1$, $\bar{E}_1$ and $\bar{F}_1$. The reshaped signals are respectively waves A_1 , B_1 , C_1 , D_1 , E_1 and F_1 shown in FIG. 8 and the outputs $\bar{A}_1$, $\bar{B}_1$, $\bar{C}_1$, $\bar{D}_1$, $\bar{E}_1$ and $\bar{F}_1$ are inverted signals of the waves A_1 , B_1 , C_1 , D_1 , E_1 and F_1 shown in FIG. 8.

With reference to FIG. 5, confirmation means having 25 directional function and sequential function comprises a plurality of AND gates 16-1 to 16-15 and a plurality of bistable circuits 17-1 to 17-12. As the result of this construction, respective outputs of the AND gates 16-1, 16-2, 16-3, 16-4, 16-5, 16-6, 16-7, 16-9, 16-11, 16-13, 16-14 and 16-15 set respectively the bistable circuits 17-1 to 17-12 in confirming the length and travelling direction of the image 13 of the blip 3, while respective outputs of the AND gates 16-8, 16-10 and 16-12 reset respectively the bistable circuits 17-7, 17-8 and 17-9. Other bistable circuits 17-1, 17-2, 17-3, 17-4, 17-5, 17-6, 17-10, 17-11 and 17-12 are reset by the signals $\bar{A}_1$, $\bar{B}_1$, $\bar{C}_1$, $\bar{A}_1$, $\bar{B}_1$, $\bar{C}_1$, $\bar{D}_1$, $\bar{E}_1$ and $\bar{F}_1$ respectively as shown.

With reference to FIG. 6, memory means and means for sensing from the means shown in FIG. 5 additive confirmation signals α and $\bar{\alpha}$ subtractive confirmation signals β and $\bar{\beta}$, an additive counting-pulse $Cp+$ and a subtractive counting pulse $Cp-$ comprises six AND gates 18-1 to 18-6, four bistable circuits 19-1 to 19-4 and two blocking oscillators 20-1 and 20-2. The additive confirmation signal α and the subtractive confirmation signal $\bar{\beta}$ are employed to control the AND gates 16-1, 16-2, 16-3, 16-7, 16-9 and 16-11 so as to determine whether a travelling image 13 of the blip 3 is to be counted or not.

In the above-mentioned, all of the bistable circuits 17-1 to 17-12 and the bistable circuits 19-1 to 19-4 are designed so as to be reset to the respective reset states in which respective outputs A_2 , B_2 , C_2 , A_3 , B_3 , C_3 , D_2 , E_2 , F_2 , D_3 , E_3 , F_3 , α , $\bar{\beta}$, M and N assume ON-states when the power is supplied. However, these means are not shown in FIGS. 5 and 6 for simple illustration.

In operation, if the microfilm 7 is shifted in the normal travelling direction $Ad+$, the image 13 of the blip 3 is shifted as shown in FIG. 7 so as to successively cover the photosensitive means A,B,C,D,E and F. In response to these successive shifting of the image 13 of the blip 3, waves shown in FIG. 8 are generated at respective corresponding parts of the circuits shown in FIGS. 4, 5 and 6. In this case, respective memory elements A_2 , B_2 and C_2 of the bistable circuits 17-1, 17-2 and 17-3 are set by respective outputs of the AND gates 16-1, 16-2 and 16-3 operating in confirming the length and shifted direction of the image 13 of the blip 3. The outputs A_2 , B_2 and C_2 are applied to the AND gate 18-3, so that an additive memory output M of the bistable circuit 19-3 assumes ON-state at a time T_4 and assumes OFF-state at a time T_7 . Accordingly, the blocking oscillator 20-1 generates the additive counting pulse $Cp+$ at the time T_7 . On the other hand, respective memory elements D_3 , E_3 and F_3 of the bistable circuits 17-10, 17-11 and 17-12 are set by respective outputs of the AND gates 16-13, 16-14 and 16-15 operating in confirming

the length and shifted direction of the image 13 of the blip 3 similarly as the memory elements A_3 , B_3 and C_3 of the bistable circuits 17-1, 17-2 and 17-3. The outputs D_3 , E_3 and F_3 are applied to the AND gate 18-1, so that the bistable circuit 19-1 is controlled so as to generate the additive confirmation signal α at a time T_8 . If the microfilm 7 is shifted thereafter in the same normal travelling direction $Ad+$, the additive confirmation signal α assumes continuously the ON-state, while respective memory elements A_2 , B_2 , C_2 , D_3 , E_3 , F_3 and M of the bistable circuits 17-1, 17-2, 17-3, 17-10, 17-11, 17-12 and 19-3 repeat ON-OFF operations in response to every passing of the image 13 of the blip 3 as shown in FIG. 8. In each of the ON-OFF operations, the additive counting-pulse $Cp+$ is generated at the T_7 .

If the microfilm 7 is shifted in the reverse travelling direction while driven in the normal travelling direction as a result of fluctuation of the shifted direction caused by switching the travelling speed, the image 13 of the blip 3 is shifted so as to successively assume relative positions of times T_{11} to T_1 in FIG. 7. In this case, the image 13 of the blip 3 cover successively the photosensitive means D, E and F from the direction from "F" to "D", while respective memory elements D_2 , E_2 and F_2 of the bistable circuits 17-7, 17-8 and 17-9 are not set since the respective AND gates 16-7, 16-9 and 16-11 are closed in response to the OFF-state of the additive-confirmation signal $\bar{\alpha}$. Accordingly, since the memory element N of the bistable circuit 19-4 pulse assumes the OFF-state, the subtractive counting pulse $Cp-$ is not also generated. If the image 13 of the blip 3 is further shifted on the photosensitive means C to A in the direction from "C" to "A", respective memory elements C_3 , B_3 and A_3 of the bistable circuits 17-6, 17-5 and 17-4 are turned to the ON-state in confirming the length of the image 13 of the blip 3 so that the additive confirmation signal α and the subtractive confirmation signal β assume the OFF-state and the ON-state respectively at a time T_4 . Thereafter, if another image 13 of the blip 3 is shifted in the reverse travelling direction so as to cover the photosensitive means A,B,C,D,E and F as shown in FIG. 9, waves shown in FIG. 10 are generated at corresponding parts of the circuits shown in FIGS. 4, 5 and 6 while the additive confirmation signal α and the subtractive confirmation signal β are still maintained at the OFF-state and ON-state respectively. Accordingly, the subtractive counting-pulse $Cp-$ is generated at a time T_{4a} for each image 13 of the blip 3. Moreover, if the image 13 of the blip 3 is shifted again in the normal travelling direction so that the image 13 of the blip 3 returned across the photosensitive means A,B,C,D,E and F passes from the photosensitive means A to the photosensitive means F, the additive confirmation signal α and the subtractive confirmation signal β assume respectively the ON-state and the OFF-state at a time T_8 so that the additive counting-pulse $Cp+$ is generated for each image 13 from the next one of the image 13.

If the microfilm 7 is shifted in the reverse travelling direction $Ad-$, the image 13 of the blip 3 is shifted as shown in FIG. 9. In this case, waves shown in FIG. 10 are generated at respective corresponding parts of circuits shown in FIGS. 4, 5 and 6. In this case, respective memory elements F_2 , E_2 and D_2 of the bistable circuits 17-9, 17-8 and 17-7 are set by respective outputs of the AND gates 16-11, 16-9 and 16-7 and reset by respective outputs of the AND gates 16-12, 16-10 and 16-8. These AND gates 16-7 to 16-12 operate in confirming the length and shifted direction of the image 13 of the blip 3. The outputs F_2 , E_2 and D_2 are applied to the AND gate 18-5, so that a subtractive memory output N of the bistable circuit 19-4 assumes ON-state at a time T_{4a} . At this time T_{4a} , the blocking oscillator 20-2 is controlled so as to generate the subtractive counting-pulse $Cp-$. At a time T_{7a} , the memory element N of the bistable circuit 19-4 is turned to the OFF-state. Moreover, respective memory elements C_3 , B_3 and A_3 of the bistable circuits 17-6, 17-5 and 17-4 are set, similarly as the memory element F_2 , E_2 and D_2 , by respective outputs of the AND gates 16-6, 16-5 and 16-4 operating in confirming

the length and shifted direction of the image 13 of the blip 3. The outputs C_3 , B_3 and A_3 are applied to the AND gate 18-2, so that the bistable circuit 19-2 is controlled so as to the subtractive confirmation signal β to the ON-state at a time T_4 . If the microfilm 7 is shifted thereafter in the same reverse direction A_{d-} , the subtractive confirmation signal β assumes continuously the ON-state, while respective memory elements F_2 , E_2 , D_2 , C_2 , B_2 , A_2 and N of the bistable circuits 17-9, 17-8, 17-7, 17-6, 17-5, 17-4 and 19-4 repeat ON-OFF operations in response to every passing of the image 13 of the blip 3 as shown in FIG. 9. In each of the ON-OFF operations, the subtractive counting-pulse C_{p-} is generated at the time T_{4a} .

If the microfilm 7 is shifted in the normal travelling direction while driven in the reverse travelling direction as a result of fluctuation of the shifted direction caused by switching the travelling speed, the image 13 of the blip 3 is shifted so as to successively assume relative positions of time T_{11a} to T_{1a} in FIG. 9. In this case, the image 13 of the blip 3 cover successively the photosensitive means A, B and C from the direction from "A" to "C", while respective memory elements A_2 , B_2 and C_2 of the bistable circuits 17-1, 17-2 and 17-3 are not set since the respective AN gates 16-1, 16-2 and 16-3 are closed in response to the OFF-state of the subtractive confirmation signal β . Accordingly, since the memory element M of the bistable circuit 19-3 assumes the OFF-state, the additive counting-pulse C_{p+} is not also generated. If the image 13 of the blip 3 is further shifted from the photo-sensitive means D, E and F in the direction "D" to "F", respective memory elements D_3 , E_3 and F_3 of the bistable circuits 17-10, 17-11 and 17-12 are turned to the ON-state, so that the additive confirmation signal α and the subtractive confirmation signal β assume respectively the ON-state and the OFF-state at the time T_{4a} . Thereafter, if another image 13 of the blip 3 is shifted in the normal travelling direction so as to cover the 35 photosensitive means A, B, C, D, E and F as shown in FIG. 7, waves shown in FIG. 8 are generated at corresponding parts of the circuits shown in FIGS. 4, 5 and 6 while the additive confirmation signal α and the subtractive confirmation signal β are still maintained at the ON-state and OFF-state respectively. Accordingly, the additive counting pulse C_{p+} is generated at a time T_7 for each image 13 of the blip 3. Moreover, if the image 13 of the blip 3 is shifted again in the reverse travelling

direction so that the image 13 of the blip 3 returned across the photosensitive means A, B, C, D, E and F passes from the photosensitive means F to A, the additive confirmation signal α and the subtractive confirmation signal β assume respectively the OFF-state and the ON-state at a time T_{4a} so that the subtractive counting pulse C_{p-} is generated for each image 13 from the next one of the image 13.

What I claim is:

1. In a system for automatically searching out a desired frame from a microfilm travelling along a guide path by counting the number of detected pulses generated in response to optical direction of each blip printed on a corresponding blank space of each frame of the microfilm, the improvement comprising:

15 a screen on which the microfilm frames are successively projected and having two groups of ON-OFF photosensitive means in each of which the photosensitive means are arranged to detect the dimensional magnitude of the images of the individual blips on the screen, confirmation means confirming the dimensional magnitude of the image of the individual blips successively in response to ON-states of all the photosensitive means in view of directional information determined in the order of switching into the ON-states of respective photosensitive means included in one of the two groups of the photosensitive means selected in accordance with the travelling direction of the microfilm, means for generating successive confirmation pulse signals successively each time all the photosensitive means included in the other of the two groups assume ON-states in accordance with a direction defined by the directional information, memory means for storing the directional information during a time between two next successive confirmation signals; and

20 output means for sensing the confirmation signal as the detected pulses only when the directional information corresponds to the predetermined travelling direction of the microfilm.

2. A system according to claim 1, in which each blip has a 25 rectangular configuration, and in which said photosensitive means are arranged on the screen to confirm to the length of the image of the individual blips.
